UNITED STATES PATENT OFFICE.

JOHN KORZENIEWSKI, OF TOLEDO, OHIO.

BALLOON.

1,225,139.

Specification of Letters Patent.

Patented May 8, 1917.

Application filed October 16, 1916. Serial No. 125,879.

To all whom it may concern:

Be it known that I, JOHN KORZENIEWSKI, a subject of the Czar of Russia, residing at Toledo, in the county of Lucas and State of Ohio, have invented certain new and useful Improvements in Balloons, of which the following is a specification.

This invention relates to certain new and useful improvements in balloons.

10 The main object of the present invention is to provide a balloon especially adapted to convey gas from one point to another and including means for liberating the gas at certain intervals of time and distances.

15 A further object of the invention is to provide a balloon in which the bag thereof is adapted to contain a gas with time and distance controlled means associated with said gas bag for puncturing the same to 20 permit the gas to be liberated at the desired time and point.

With the above general objects in view and others that will appear as the nature of the invention is better understood, the same 25 consists in the novel construction, combination and arrangement of parts to be herein-after more fully described and then claimed.

In the accompanying drawing forming a part of this application and to which reference is had herein by like characters designating corresponding parts throughout the several views:

Figure 1 is a side elevational view of a balloon constructed in accordance with the 35 present invention, the gas bag thereof being partly shown in section while the motor supporting carriage is shown in longitudinal section better to illustrate the interior thereof.

40 Fig. 2 is an enlarged elevational view of the timing mechanism and balloon puncturing apparatus detached from the carriage.

Fig. 3 is a top plan view of the mechanism shown in Fig. 2, and

45 Fig. 4 is an enlarged sectional view of the spring operated balloon piercing projectile.

The present invention aims to provide a balloon that is especially adapted and constructed for use to convey gases from one point to another, and in which the bag portion of the balloon may be formed of any suitable material such as silk and is adapted to contain gas. A carriage is suspended 50 from the gas bag and carries the motor mechanism for forwardly propelling the

balloon, and this carriage also supports a distance and time controlled tensioned projectile that is adapted to be released and shot through the gas bag at the desired time 66 and point to liberate the gas contained therein for purposes as will be clearly evident.

Referring more in detail to the accompanying drawing, and particularly to Fig. 65 1, the reference numeral 5 designates the gas bag portion of the balloon and has suspended therefrom the mechanism supporting carriage 6. It is to be understood that the gas bag may be formed of any suitable 70 material as aluminum or silk, as the occasion may require.

The gas bag 5 is of the usual oval shape and is connected at its lower side to the flanges 7 on the carriage 6. The balloon is 75 adapted to ascend and travel forwardly without the services of an operator and the carriage 6 may, therefore be constructed of a size alone to include the motor mechanism and bag puncturing mechanism. A standard 80 8 is positioned in the carriage 6 and has journaled in the upper end thereof the horizontal propeller shaft 9 which extends through a journal bearing 10 in the rear end of the carriage 6 and has fixed upon the 85 outwardly projecting end thereof a propeller wheel 11. A pinion 12 is fixed to the shaft 9 adjacent the standard bearing 8 and is in constant mesh with the gear 13 carried on the shaft of the motor 14. The motor 90 has the usual wire connection 15 with the battery 16, the line wire connection 15 being switch controlled as at 17. It will therefore be seen that upon the closing of the switch 17, the motor 14 will be operated 95 and through the meshing gear and pinion 13 and 12 respectively the propeller 11 will be driven to forwardly propel the balloon.

Mechanism is provided for puncturing the gas bag 5 at the desired time and distance 100 from the point despatched and includes a casing 18 fixed to the bracket 19 within the carriage 6 at a point directly beneath the gas bag 5. Clock mechanism of usual construction is contained within the casing 18 and it is deemed unnecessary to herein illustrate the same in detail, it being noted however that there is provided as shown in Fig. 3, a stem 20 to wind the mechanism spring, a stem 21 to set the timing mechanism and 110 a stem 22 for correctly positioning the timer. The face of the casing 18 includes a dial 23

1,225,189

having a circular series of distance numerals 24 thereon with an indicator hand 25 associated with such numerals. The smaller dial 26 includes the indicator hand 27 for setting the timing mechanism similar to the alarm mechanism of an ordinary clock. An angular arm 28 projects upwardly from the casing 18 and is adapted at a predetermined instant to vibrate as shown by dotted lines 10 similar to the hammer of an alarm clock and during such vibratory movement engages the flat rear face 29 of a cam member 30 that is pivotally supported as at 31 on the standard 32 carried by the upper side of the 15 casing 18. A vertically disposed cylinder 33 is supported laterally of the casing 18, the said cylinder being open at its upper end as clearly shown in Figs. 2 and 4 for the reception of a compression coil spring 34 which engages the closed lower end of the 20 cylinder 33, the said spring being compressed by the projectile 35 received in the upper end of the cylinder and retained therein by the pin 36 on the projectile received in the bayonet slot 37 in the upper end of the cylinder 33 as is clearly shown in Fig. 2. A bearing 38 is carried by the casing 18 and has slidably disposed in the upper end thereof a horizontal rod or pin 39 that is adapted to be engaged at one end by the cam 30 while the other end thereof is adapted to be moved into engagement with the pin 36 upon the projectile to move the same relative to the bayonet slot 37 whereby the compressed coil spring 34 within the cylinder 25

may suddenly project the same to cause the projectile to pass completely through the gas bag 5 for puncturing the same so that gas contained therein may be liberated.

From the above detailed description of the invention, it is thought that the construction and operation will be readily apparent, and while the form of the invention herein shown and described is what is believed to be the preferred embodiment thereof, it is nevertheless to be understood that minor changes may be made in the form, proportion and details of construction without departing from the spirit and scope of the invention as hereinafter claimed.

What I claim as new is:—

A device of the class described comprising a gas bag inflated with gas, a carriage suspended thereby, a propeller and motor mechanism therefor supported by said carriage, a clock mechanism and casing therefor supported within said carriage beneath said gas bag, a cylinder supported by said clock casing, a tensioned projectile within said cylinder, a sliding pin supported by said clock casing, a cam supported by said clock casing and means operated by the clock mechanism for shifting the cam into engagement with the said pin whereby the pin is caused to engage the projectile to release the same from the cylinder for puncturing the gas bag.

In testimony whereof I affix my signature.

JOHN KORZENIEWSKI.
